MANUALLY OPERABLE POSITIVELY DRIVEN
LOOM THREAD HOLDERWalter H. Wakefield, Worcester, Mass., assignor
to Crompton & Knowles Loom Works, Worcester, Mass., a corporation of Massachusetts

Application May 6, 1944, Serial No. 534,471

8 Claims. (Cl. 139—247)

This invention relates to improvements in thread holders for the weft ends of reserve bobbins in weft replenishing looms and it is the general object of the invention to provide positively acting driving mechanism for thread engaging gears so constructed that the latter can be turned manually to tension weft ends while still connected to their driving mechanism.

Weft replenishing looms more particularly of the multicolor type employ several stacks of bobbins from which weft ends extend to a thread holder. For proper operation of the loom it is necessary to keep these weft ends under tension sufficient to hold them above the lay which reciprocates below the bobbin magazine. It has been proposed heretofore to employ a pair of thread engaging gears between which the weft ends extend and mounted so that they can be rotated in such a direction as to draw the weft ends in a direction away from the magazine. When the threads extending from the bobbins are coarse they impose considerable load on the gears and devices heretofore employed for turning the gears are not always satisfactory, particularly if a large number of coarse threads or weft ends lie between the gears.

When fresh bobbins are placed in the magazine their weft ends are drawn off and laid across the gears which are then turned manually to draw the new or additional weft ends between them and also establish proper tension. It is an important object of my present invention to provide means for driving the thread gears slowly and at a uniform rate to keep the weft ends under constant tension and construct the driving mechanism so that it will be in driving relation with the thread gears at all times but permit said gears to be turned manually for the purpose of tensioning new weft ends.

It is a more particular object of my present invention to provide planetary gearing between the thread engaging gears and some part of the loom which rotates during loom operation. Because of its location and slow rate of turning it is convenient to use the take-up roll to supply the driving force for the planetary gearing, but any other regularly rotating part of the loom suitable for the purpose can be used to supply the driving force. The planetary gearing is so constructed that the planet gear or pinion which is the driven member of the unit is connected to the thread gears, as by a flexible shaft, to cause them to turn under normal conditions. The planet pinion is mounted so that it can swing

around the axis of a solar gear to permit manual operation of the thread gears.

The weft ends ordinarily impose resistance to the turning of the thread gears and when the latter are manipulated to tension new weft ends the planet gear swings to a non-operating position where it is held against rotation by the weft ends. This is particularly true after fresh bobbins have been placed in the magazine and a large bundle of threads lie between the thread gears. Since the planet pinion is not free to rotate on its axis at this time it will be moved back to normal position by continued rotation of the solar gear, after which the pinion starts to rotate. After the planet gear has moved away from its normal driving position there will be a brief period during which the thread gears are not turned, but this time will ordinarily occur immediately after the operator has tensioned the weft ends by a turning of the thread gears and there is very little likelihood that objectionable slackness will develop in the weft ends before the planet pinion is returned to its normal position.

With these and other objects in view which will appear as the description proceeds, my invention resides in the combination and arrangement of parts hereinafter described and set forth.

In the accompanying drawings, wherein a convenient embodiment of my invention is set forth, Fig. 1 is a front elevation of one end of a weft replenishing loom showing my invention applied thereto,

Fig. 2 is a detailed plan view looking in the direction of arrow 2, Fig. 1, showing the relation of the magazine, the thread holder and flexible shaft which drives the thread gears,

Fig. 3 is a diagrammatic view showing normal operating conditions and indicating the directions of rotation of the solar, planet and thread gears when looking in the direction of arrow 3, Fig. 1,

Fig. 4 is similar to Fig. 3 but shows the conditions existing immediately after manual turning of the thread gears,

Fig. 5 is an enlarged vertical section on line 5—5 of Fig. 2,

Fig. 6 is an enlarged vertical section on line 6—6 of Fig. 1, showing the planet pinion in working position and also in intermediate and extreme non-working positions, and

Fig. 7 is a plan view of the structure shown in Fig. 6, the planet pinion and its support arm corresponding to the intermediate dotted line position of Fig. 6.

Referring particularly to Fig. 1, I have shown

a loom frame 10 having a lay 11 on which is mounted a shuttle 12 located under a bobbin magazine M on alternate picks of the loom when the lay is preferably on front center position. The magazine as indicated in Fig. 2 is provided with four stacks of reserve bobbins B the weft ends W of which extend to a thread holder indicated generally at H. The thread holder has front and back thread engaging geared members 13 and 14, respectively, which in practice are gears made of Bakelite and having smooth teeth which do not abrade the threads. These gears are mounted on a casing or support 15 held at the outer end of a support arm 16 the left end of which as indicated in Figs. 1 and 2 is held at 17 to some part of the magazine, such as a tie rod 18, extending between the inner and outer magazine bobbin guiding plates 19 and 20, respectively, between which the reserve bobbins lie.

During loom operation the bobbins B have a tendency to rotate on their axes in such directions as to slacken their weft ends and it is desirable that provision be made for turning the thread gears 13 and 14 to take up this slackness. At the time of transfer operation one or another of the reserve bobbins is pushed downwardly into the shuttle 12 in well-known manner and all the other bobbins in the corresponding stack fall with an accompanying slackness of their weft ends. This slackness also should be taken up by rotation of the thread gears so that the threads W will be kept above the path of the lay 11.

The front part of the loom is provided with a breast beam 25 on which is rotatably mounted a cloth or fabric take-up roll 26 rotatable in bearings extending forwardly from the breast beam. In Figs. 6 and 7 one of these bearings is indicated at 27 and receives a gudgeon 28 projecting from the adjacent end of the take-up roll. During loom operation the take-up roll is rotated in the direction of arrow a, Fig. 6, to advance the fabric F as the latter is woven. The driving mechanism for the take-up roll has been omitted from the drawings since it is well understood and is ordinarily located on that end of the loom opposite the magazine. The bearing 27 may if desired be formed with a cap 29 held to the main part of the bearing by bolts 30.

The thread holder casing or support 15 may comprise a box-like structure 35 having a vertical web 36 provided with a bearing 37 through which extends a short shaft 38. This shaft is made with a flange 39 and has its outer end reduced at 40 to receive a nut 41. The front thread gear 13 is clamped between the flange 39 and the nut 41, as will be apparent from Fig. 5, so that whenever the shaft 38 turns the thread gear 13 will turn with it and cause rotation of thread gear 14 with which it meshes.

The matter thus far described may be of the usual construction, those parts of the thread holder already described being substantially the same as set forth in certain prior patents to Payne such for instance as Patent No. 1,842,731.

In carrying my present invention into effect I provide a driving connection between thread gear 13 and a member which rotates during loom operation, such as the take-up roll. As shown in Fig. 5 the left end of short shaft 38 has a tapered thread 45 and is split as at 46 to receive the core 47 of a flexible shaft 48 having a sheath 49. A nut 50 having tapered internal threads surrounds the tapered threads 45 and when set up to the position shown in Fig. 5 clamps the split end of shaft 38 against the shaft core. In this way the

shaft 38 is required to turn whenever the core 47 rotates.

As shown more particularly in Fig. 1 the flexible shaft extends across the front of the magazine to mechanism associated with the take-up roll. In order to support the shaft I extend one of the tie rods 53 beyond the outer magazine plate 20 and secure thereto the hub 54 of a small arm 55 inclined downwardly and outwardly and having an upturned end 56 through which the shaft 48 passes. Clips 57 and 58 on the outer and inner magazine end plates 20 and 19, respectively, hold the intermediate part of the shaft in fixed position, while a guide 59 secured to the loom frame, see Figs. 1 and 7, affords guiding support for the end of the flexible shaft adjacent to the take-up roll. The shaft is free to move slightly with respect to the upturned end 56 of arm 55, and is also capable of slight longitudinal motion through 20 the guide 59, so that the ends of the shaft are capable of slight movement relatively to the magazine and loom frame 10.

A planetary gearing mechanism, such as shown more particularly in Figs. 6 and 7, is operatively connected to the take-up roll 26 and to the flexible shaft 48. As shown in Fig. 7 the gudgeon 28 of the take-up roll has tapped thereto the threaded end 65 of a stud 66 preferably coaxial with the take-up roll. A solar driving gear or member 67 is pinned as at 68 to the stud 66 and therefore rotates with the take-up roll whenever the latter turns. A support arm or lever 70 has a hub 71 freely rotatable on the stud between the gear 67 and a stop pin 72. As shown in Figs. 6 and 7 an arm 75 extends from the hub 71 and has formed thereon a bearing 76 in which rotates a shorter stub shaft 77. The inner or right end of this shaft 77 as viewed in Fig. 7 has a driven planetary pinion, gear or member 78 held thereto by pin 79. The pinion is thus mounted on support 70 for rotation about its axis and also revolution about stud 66. The left end of shaft 77, see Fig. 7, is connected to the core 47 of the flexible shaft in a manner similar to that already described in connection with Fig. 5. For this purpose a nut 80 when set up tight on the tapered threads 81 of shaft 77 clamps the latter tightly to the core 47 of the flexible shaft.

The pinion support means comprises an arm 70 provided with a counterweight 82 which is not quite heavy enough to balance arm 75 and the structure carried by it, but is sufficiently heavy so that only a slight force is required to hold arm 75 in the position shown in full lines in Fig. 6. The cap 29 of the bearing 27 is provided with upper and lower stop pins 84 and 85, respectively, positioned for engagement with the counterweight 82 to limit angular movement of the support 70 around stud 66. Ordinarily the counterweight is in engagement with the lower stop pin 85 and the pinion is in the high position shown in full lines in Fig. 6.

In normal operation, the flexible shaft causes the planet pinion to rotate in unison with the gears 13 and 14, and rotation of the take-up roll causes the solar or driving gear 67 to turn in the direction of arrow a, Fig. 6. Since the counterweight engages stop pin 85, the pinion 78 is held with its axis stationary and caused to rotate in a clockwise direction as viewed in Fig. 6, thus turning the core 47 of the flexible shaft to rotate thread gears 13 and 14. Arrows in Fig. 3 indicate the direction in which the gearing turns under normal conditions, and suggest that the

thread gears turn in such a direction as to tension the weft ends W.

The pinion 78 turns during loom operation to subject the weft ends to continuous tension to take up slackness which may result either from rotation of the bobbins or transfer operations of the magazine. When it is necessary to place a fresh supply of bobbins in the magazine their weft ends will ordinarily be drawn off and laid over the gears 13 and 14, after which the latter will be turned manually by the operator at a rate faster than their normal rate of turning in order to draw the new or additional weft ends between the thread gears and tension them. At this time the core 47 is given a quick right hand rotation as viewed in Fig. 3 and causes the pinion to roll around the solar gear in a clockwise direction as viewed in Fig. 6. If the thread gears have been given only a slight turning the planetary pinion may move to some such position as I, see Fig. 6, but if they have been given a greater turning movement the pinion will move to the low position indicated at II with the counterweight in engagement with the upper stop pin 84. In common practice less than a complete rotation of the thread gears is necessary in order to establish proper holding relation with the new weft ends and the pinion 78 may not always occupy position II.

The additional weft ends from the bobbins newly placed in the magazine will offer increased resistance to turning of the thread gears 13 and 14 and this resistance will be sufficient to prevent the pinion 78 from turning on its axis. When the planetary system is therefore in the position shown in Fig. 4 the pinion is unable to turn on its axis either to the right or left but is caused to maintain a non-rotary relationship with respect to the support 10. Under these conditions gears 13 and 14, and the pinion are held against rotation, as suggested in Fig. 4 by absence of certain arrows shown in Fig. 3. As gear 67 continues to turn the pinion rises in the direction of arrow b, Fig. 4, until the counterweight again engages the stop pin 85. The pinion is then no longer able to travel around the solar gear and begins to rotate on its axis. The force derived from the solar gear is ample to overcome the resistance of the weft ends between the thread gears 13 and 14. Thus it is that after the thread gears have been given a rapid movement to tension new weft ends the gear 67 acts in conjunction with the resistance to turning of the thread gears offered by the weft ends to restore the pinion to its normal working position.

From the foregoing it will be seen that I have provided driving connections between a rotating part of the loom and the thread gears comprising planetary gearing the solar gear of which turns regularly during loom operation and the planet gear or pinion of which is normally turned to cause rotation of the thread gears, through rotary driving mechanism or connecting means, which in the present instance is the flexible shaft 48. It will also be seen that when the thread gears are manually turned faster than normal rotation in order to tension new weft ends the planet gear rolls around the solar gear in a direction opposite to that in which the solar gear turns to some such position indicated either I or II in Fig. 6. During this operation the driving connections between the take-up roll and the thread gears are maintained and the gear 67 and pinion 78 remain in mesh. Furthermore, resistance to turning of pinion 78 because of the pres-

ence of weft ends between the thread gears causes the solar gear to return the planet gear to its normal working position, after which turning of the thread gears is resumed. In considering certain features of the invention the shaft 71 may be considered as the planetary member while the pinion 78 constitutes a driving connection between it and the solar gear.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom having reserve bobbins from which weft ends extend to meshing geared members rotatable to tension said weft ends, a driving gear rotating during loom operation, a driven gear continuously meshing with said driving gear, connecting means causing said driven gear and one of said geared members to rotate in unison, support means mounting the driven gear for bodily movement about the axis of the driving gear from working position to a non-working position, and a stop normally engaging the support and cooperating with the driving gear to hold the driven gear in working position and cause rotation of the driving gear to turn the driven gear and geared members to tension the weft ends, the weft ends preventing substantial rotation of said geared members when the driven gear is in non-working position and preventing rotation of the driven gear and causing continued turning of the driving gear to effect return of the driven gear to working position.

2. In a weft replenishing loom having reserve bobbins from which weft ends extend to meshing thread gears rotatable to tension said weft ends, a solar driving member rotating during loom operation, a driven rotatable planetary member, means mounting the driven member for movement to different positions, driving connections between said members causing them to be in driving relationship for all positions of the driven member, stop means normally cooperating with the driving member to maintain the driven member in a given position in which the driven member is caused to rotate by the driving member to turn the thread gears to tension the weft ends, connecting means between one of the thread gears and said driven member causing the latter to turn in unison with said thread gears, the driving member and connecting means normally causing the thread gears to turn to tension the weft ends, the weft ends preventing substantial rotation of the thread gears and driven member when the latter is in any of said positions except said given position and preventing rotation of the driven member and causing the driving member acting through said driving connections to return said driven member to said given position.

3. In a weft replenishing loom having reserve bobbins from which weft ends extend to meshing geared members rotatable to tension said weft ends, actuating means rotating during loom operation, a driving gear rotating with said actuating means, a driven gear continuously meshing with said driving gear, connecting means causing said driven gear and one of said geared members to rotate in unison, support means mounting the driven gear for bodily movement about the axis of the driving gear from working position, to a non-working position, and a stop normally engaging the support and cooperating with the driving gear to hold the driven gear in working

position and cause rotation of the driving gear to turn the driven gear and geared members to tension the weft ends, the weft ends preventing substantial rotation of said geared members when the driven gear is in non-working position and preventing rotation of the driven gear and causing continued turning of the driving gear to effect return of the driven gear to working position.

4. In a weft replenishing loom having reserve bobbins from which weft ends extend to meshing geared members rotatable to tension said weft ends, a cloth take-up roll rotating during loom operation, a driving gear rotating with said take-up roll, a driven gear continuously meshing with said driving gear, connecting means causing said driven gear and one of said geared members to rotate in unison, support means mounting the driven gear for bodily movement about the axis of the driving gear from working position to a non-working position, and a stop normally engaging the support and cooperating with the driving gear to hold the driven gear in working position and cause rotation of the driving gear to turn the driven gear and the geared members to tension the weft ends, the weft ends preventing substantial rotation of said geared members and driven gear when the latter is in non-working position, and causing continued turning of the driving gear to return the driven gear to working position.

5. In a weft replenishing loom having reserve bobbins from which weft ends extend to meshing geared members rotatable to tension said weft ends, a cloth take-up roll rotating during loom operation, a solar gear rotating with said take-up roll, a planet gear meshing with said solar gear, a support for the planet gear with respect to which the latter rotates, means mounting the support for movement angularly about the axis of the solar gear, rotary driving mechanism causing said planet gear and one of the geared members to rotate in unison when either the planet gear or said one geared member rotates, and a stop limiting angular movement of the support in the direction in which the solar gear turns and effective when engaging said support to cause the solar gear to turn the planet gear and thereby effect turning of said geared members to tension said weft ends at a given rate dependent upon the rate of turning of the take-up roll, said geared members when rotated manually faster than said given rate to tension additional weft ends causing said planet gear to roll along the solar gear and move said support away from said stop, the additional weft ends acting through said geared members and rotary driving mechanism to prevent substantial rotation of said planet gear relatively to the support and causing said solar gear as the latter continues to rotate to move the support back into engagement with said stop.

6. In a weft replenishing loom having reserve bobbins from which weft ends extend to meshing geared members rotatable to tension said weft ends, a cloth take-up roll rotating during loom operation, a gear rotating with said take-up roll, a pinion meshing with said gear, a support on which the pinion is rotatably mounted, means mounting the support for angular movement about the axis of the gear, connections causing the pinion and one of said geared members to rotate in unison, and a stop limiting angular movement of said sup-

port in the direction in which the gear turns, said gear normally turning said pinion and effecting rotation of the geared members at a given rate to tension the weft ends when said support engages said stop, said geared members when rotated manually at a rate faster than said given rate to tension additional weft ends causing said pinion to roll around said gear and move the support away from said stop, said weft ends holding the geared members substantially stationary and preventing substantial rotation of the pinion relatively to said support and causing continued turning of said gear to move said support back into engagement with said stop.

7. In a weft replenishing loom having reserve bobbins from which weft ends extend to meshing geared members rotatable to tension said weft ends, a cloth take-up roll rotating during loom operation, a solar gear rotating with said take-up roll, a planet pinion meshing with the solar gear, means mounting said planet pinion for rotation on its axis and revolution about the gear while meshing with the latter, connections causing the pinion and one of the geared members to rotate in unison, and a stop limiting revolving movement of the planet pinion about the solar gear in the direction in which the latter turns and normally cooperating with the solar gear to maintain the planet pinion in operating position, said gear turning the pinion when the latter is in operating position to effect turning of the geared members at a given rate to tension said weft ends, said geared members when manually rotated at a rate faster than said given rate to tension additional weft ends causing the pinion to revolve about the gear in a direction opposite to the direction in which the gear turns and move to a non-operating position, the weft ends preventing substantial rotation of said geared members and pinion by said gear when the pinion is in non-operating position and causing continued turning of the gear to effect return of the pinion to operating position.

8. In a weft replenishing loom having reserve bobbins from which weft ends extend to meshing geared members rotatable to tension said weft ends, a cloth take-up roll rotating during loom operation, a gear secured to and rotating with said take-up roll, a pinion meshing with said gear, a support mounting the pinion for rotation on its axis and revolution about the axis of the gear, a flexible shaft causing the pinion and one of said geared members to rotate in unison, and a stop for said support limiting angular movement thereof in the direction in which the gear turns, said gear turning said pinion to turn said shaft to effect rotation of the geared members at a given rate to tension the weft ends when said support engages said stop, said geared members when rotated manually at a rate faster than said given rate to tension additional weft ends causing said flexible shaft to turn said pinion and cause the latter to roll around said gear and move the support away from said stop, said geared members thereafter being held substantially stationary by said additional weft ends to prevent substantial rotation of the pinion relatively to said support, and continued turning of said gear resulting in movement of said support back into engagement with said stop.

WALTER H. WAKEFIELD.
